REEL ARBOR LOCK

Carl O. Bruestle, Metuchen, N. J., assignor to
 Syncro Machine Company, Perth Amboy, N. J.,
 a corporation of New Jersey

Application December 8, 1951, Serial No. 260,731

1 Claim. (Cl. 242—139)

1

This invention relates to a mechanism for locking a reel of material in a strand handling machine.

In various kinds of operations involving wire handling, either the winding or twisting thereof, reels of wire must be assembled in a cradle and held in position while it is fed off at the rate demanded by the particular operation being performed. In general, a strand or wire handling machine will include a cradle or cradles, means for feeding the wire from reels held in the cradles, guides, driving mechanism and a delivery capstan for taking the completed product. If the machine is a high-speed one, the problem of mounting the wire reel becomes a difficult one, for the safety of the operator must be kept paramount.

Where high-speed stranding machines employ reels of wire which are mounted in cradles, locking mechanisms have been provided which correspond approximately to a sliding bolt which is slipped across into an opening for the reel arbor. Where reliance must be placed upon a human operator to perform a relatively complicated locking operation, failure is bound to occur and, with the high-speed machines, results are generally tragic. It is accordingly a fundamental object of the instant invention to provide a locking structure for a reel which can be completely operated from one side of the machine and which has the further virtue of being simple in its operation.

It is a second object of the invention to provide a reel arbor lock combination for use with the cradle of a stranding machine which will reduce the locking operation to a single simple movement on the part of the operator.

Other objects and advantages of the invention will in part be obvious and in part will appear hereinafter.

The invention is accordingly embodied in an arbor lock structure wherein the ends of a stationary center arbor, which, used in carrying the reel structure are flattened at faces which are perpendicular to opposite ends of a diameter, the flat faces on each of the two ends of the center arbor shaft being substantially aligned. The structure further calls for having a key slot formed in the center support for the reel, so that a reel carried by the center arbor shaft may have its flattened ends aligned with the opening of the key-slot, dropped into place, turned 90° and pinned in that position, with the result that the center arbor shaft is permanently locked at both ends until positive release of the T-section at one end is carried out.

2

Thus the invention comprises a cradle carrying a reel supporting structure in combination with a center arbor shaft, the cradle having formed therein the necessary key-slot to receive the center arbor shaft, the structure having the features of construction, combinations of elements and arrangements of parts hereinafter to be described in further detail.

In the drawings—

10 Figure 1 is a side elevation of a cradle showing a center support carrying a locking mechanism, a brake drum and a wire reel;

15 Figure 2 is a sectional view of the cradle on the line 2—2 of Fig. 1 showing the wire reel in position and the details of the locking mechanism by taking a horizontal section at the diameter of the wire reel;

20 Figure 3 is a detailed view of the T-section end of the center arbor shaft, the section being taken at the face of the center support of the cradle;

Figure 4 is a detailed side elevation of the opposite end of the center arbor shaft;

Figure 5 illustrates a variation of the arbor and key-slot;

25 Figure 6 is a plan view of a modified type of cradle and accompanying arbor employing the reel lock in accordance with the instant invention;

Figure 7 is a side view of the reel arbor lock 30 of Fig. 6 showing the slotted key opening and brakes for the reel;

Figure 8 is a plan view of the arbor itself and, accompanying

Figures 9 and 10 are end views, respectively, 35 of the arbor shown in Figure 8.

Referring now to Figure 1, 10 represents the center support of the cradle and 11 and 12 are side extensions thereof which are integrally joined to the center support to provide means 40 for mounting the brake drum which comprises a spring mounted belt 13 pinned to the extensions at 14 and 15. The details of the braking mechanism are essentially conventional and constitute no part of the instant invention.

45 In Figure 2, the remaining details of the structure may be seen and there the opposite end of the reel may be seen carried in the center support 10'.

In Figure 2, 20 represents a reel, which in a 50 common case will be a coil of wire, mounted on the arbor carrying an antifriction rotating sleeve 21. The whole structure is carried by the stationary center arbor shaft 22 through the needle bearings 23 and 24. In assembly, the reel is slipped in place with the adjacent brake drum 18 and its collar 25 fastened to the rotating

sleeve. The reel itself drives the brake drum through pin 27. At the other end of the shaft collar 28 is mounted for adjusting the width of the reel to the length of the arbor. Washer 29 operates as a flange and is press fitted on the arbor to prevent lateral displacement of the arbor during operation of the machine.

The safety lock mechanism by which the rotating reel is held in place consists of the center support 10 having a key opening 30 formed therein, the opening being characterized by essentially a circular form in its innermost section, the approach in to the circular section being straight-sided and of a width less than a diameter of the circular opening. In effect, the outline of the opening for the reception of the center arbor shaft then becomes approximately like that of a keyhole.

The center arbor shaft, to take advantage of the keyhole, has pinned on the end thereof a T-piece 31 which has a cross-section at the plane of center support 10 like that shown in Figure 3 and is definable as essentially circular with a pair of diametrically opposed flat sections thereon. The T-piece is formed to fit the key opening in the center support, the distance between the flat portions on the T-piece being such that it will fit between the flats of the key opening on the center support. Correspondingly, the circular section of the T-piece is of a diameter matching the diameter of the circular portion of the key opening. At one side of the T-piece there is formed an opening 32 for the entry of locking pin 33 which is spring mounted by means of tension member 34 at 35 on the center support.

As shown in Figure 4, at the opposite end of the center arbor shaft, it carries a collar 37 pinned thereto which is flattened at points corresponding to the flats on the T-piece. Similarly, the key opening for receiving the center arbor shaft at this end of the cradle is that of a lock having a narrowed entrance which enlarges to a circle matching the diameter of the end collar on the center arbor shaft.

It will be evident from a consideration of Figures 3 and 4 that the same effect may be achieved by flattening the arbor shaft at one side, or by using a curved approach to the opening as shown in Figure 5, wherein 40 represents a shaft with only a single flat area to enter the narrowed opening 41.

The assembly of the apparatus and locking of a reel in place is relatively simple, for the two correspondingly oriented key openings forming the lock in the two ends of the center support are oriented in the same way. The center arbor shaft having correspondingly oriented flats on each end and carrying the antifriction mounted rotating sleeve, is slipped through a reel and the whole is lowered into place. The center arbor shaft is oriented so that the flat faces at either end thereof slide through the narrow approaches of the lock openings at each center support and, when the center arbor shaft touches the bottom of the lock opening at each end, it is turned 90° whereupon it becomes locked in position, for the full diameter of the shaft then faces the narrow approach into the lock opening. The T-piece is locked in place by permitting the spring mounted pin 33 to slide into the hole 32 in the cross-piece of the T.

When assembled, it will be seen, with the reel effectively locked in place, that high speed operation can follow and the relatively light locking mechanism is adequate to hold the reel safely in

place, for to cause the reel to be displaced from its support, it would be necessary for the diameter of the center arbor shaft to shear out a section of metal corresponding to that intercepted by the full section of the circular part of the T-piece. The reel arbor is locked against lateral displacement between washer 29 and T-piece 31 fitted thereto.

A simpler modified embodiment of the cradle may be seen by referring back to Figure 6, where 60 indicates the cradle body itself and the supports therefor, and 61 the reel arbor which is mounted in the cradle. The structure of the key openings and the ends of the arbor corresponds to that shown in connection with Figure 1, the principal difference in the instant case being that the arbor does not carry a sleeve with bearing in it, and the reel is mounted directly on the arbor. Accordingly, in the figure the arbor 61 has flats 62 and 63 (Fig. 9) on one end thereof to fit into the key opening, and at the opposite end thereof it is formed with a shoulder 64 onto which a washer 65 is press fitted to abut against the larger diameter of the arbor. Flats 66 and 67 are formed into the T-piece 68, pinned to the arbor, at this end so that it may fit the key opening 69 as indicated in Figure 7.

T-piece 68 is pinned onto the arbor at this end. The horizontal portion of the T-piece carries openings 70 into which the spring-mounted pin 71 may fit when it is locked into position. The pin is carried by tension member 72 mounted at 73. The remainder of the structure of the cradle shows an alternative to the brake drum shown in Figures 1 and 2. Thus the cradle has mounted at one end thereof a pair of blocks 81 and 82 which carry spring pivoted shoes 83 and 84 thereon to bear against the circumference of the reel 85 in order to keep it down to the speed demanded by the wire being fed out and thereby avoid "throwing a loop."

In Figure 7 the side elevation of the cradle shows clearly the key opening which comprises essentially a circular opening for the arbor having a narrow approach thereto into which the arbor carrying the T-piece is fitted. In Figs. 8 to 10 the construction of the arbor is shown more clearly and there the arbor 61 is shown with the flats 62 and 63 formed on one end and the T-piece 68 fitted on the other holding the washer 65 against abutting shoulder 64 on the arbor. The flats formed into the vertical section of the T-piece permit the arbor to enter the key opening so that when a reel is loaded in the machine the arbor as shown in Figure 8 is slipped into place and the T-piece fits directly over the support and into the key opening and is locked into place at that point. The construction of the T and the adjoining washer is such that the arbor is locked against movement out of the key opening either vertically or in the horizontal direction.

The relationship of the cradle to the tubular body 90 of the stranding machine is indicated by the dotted line in Figure 2 and in Figure 6.

Having described the invention in only a limited number of embodiments it is understood that variations in details of construction may be made without departing from the spirit or scope thereof.

What is claimed is:

In a stranding machine, structure for locking a reel in place comprising, in combination, supports for a reel, horizontally aligned key openings in said supports, each opening being characterized by having a circular load bearing sec-

tion and a narrowed entry section, a center arbor shaft spanning said supports, said shaft having at the ends thereof flattened sections to permit it to be fitted into said key openings, said shaft carrying at one end thereof a T-form flange joined thereto, the cross arm of said T being oriented parallel with said flattened sections on the end of said shaft, said flange having means thereon for receiving locking means for holding said shaft in a fixed position and an additional flange on said shaft adjacent to said flattened sections and perpendicular to the axis of said

shaft thereby with said T defining two faces in fixed spaced relation.

CARL O. BRUESTLE.
